United States Patent Office

Des. 179,143
Patented Nov. 6, 1956

179,143

CAKE OF SOAP

Gladys A. Mitchell and Robert Reed Thomas,
McFarland, Calif.

Application June 15, 1953, Serial No. 25,510

Term of patent 14 years

(Cl. D73—1)

FIG. 1.

FIG. 2.

FIG. 3.

FIG. 4.

Fig. 1 is a front elevational view of a cake of soap showing our new design;

Fig. 2 is a side elevational view of the cake of soap shown in Fig. 1;

Fig. 3 is a rear elevational view; and

Fig. 4 is a top plan view thereof.

We claim:

The ornamental design for a cake of soap, substantially as shown.
